(57) **CLAIM**

The ornamental design for an explosion-resistant weighing display, as shown and described.

DESCRIPTION

FIG. 1 is a front elevation view of an explosion-resistant weighing display;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front perspective view of thereof; and,

FIG. 8 is a front perspective view of an alternate embodiment of the explosion-resistant weighing display of FIGS. 1-7.

1 Claim, 8 Drawing Sheets
